UPHOLSTERY PAD

Application filed June 26, 1930. Serial No. 463,966.

This invention relates to methods of manufacturing upholstery padding adapted to be built into upholstery so as to lie between the springs and the finish covering, and more particularly to padding of this character suitable for use in upholstery which has a ribbed or pleated character, such as seat backs of automobiles.

It is an object of the invention to provide upholstery padding which will accentuate the ribbed construction of the finished upholstery, and give the same a well defined columnar appearance, of uniform contour and smoothly rounded throughout.

Another object of the invention is to provide a method of manufacturing continuous padding which may be cut to desired lengths for covering with finish material.

Another object of the invention is to simplify and improve the construction of upholstery padding, and to render the same economical to manufacture and otherwise well adapted for the purposes set forth.

Other objects and features of novelty will be apparent as the following description proceeds, reference being had to the accompanying drawing, in which

Figure 1 is a perspective view of upholstery padding according to the preferred embodiment of the present invention;

Fig. 2 is a vertical longitudinal section through a machine for manufacturing the padding shown in Fig. 1 and taken along the line 2—2 of Fig. 3;

Fig. 3 is a plan view of the machine illustrated in Fig. 2;

Fig. 4 is a transverse vertical section taken along the line 4—4 of Fig. 3;

Fig. 5 is a section through the padding before the same is stitched;

Fig. 6 is an enlarged cross-section of a portion of the padding shown in Fig. 1; and

Fig. 7 is a view similar to Fig. 6 but showing a modified padding.

According to the present invention, the padding is manufactured by a substantially continuous method, and produced as a roll or bolt of indeterminate length, which may be cut to desired lengths for covering with finish material. Referring more particularly to

the drawing, continuous bats 10 are supplied longitudinally in substantially parallel uniformly spaced relation, forming a layer. While seven of these bats have been shown as constituting the layer, it is to be understood that a greater or less number may be employed as desired. On one side of this layer is supplied a backing sheet 11 which is also continuous in the sense that it is of indeterminate length, and may be supplied from a large roll or bolt. On the other side of this layer is supplied a cover sheet 12 of indeterminate length. The cover sheet 12 is preferably wider than the sheet 11, and is looped smoothly over the layer of bats 10 and tucked down therebetween, and the cover sheet 12 and backing sheet 11 are secured together between the bats 10. Thus, in effect, a continuous envelope is formed, having substantially parallel longitudinally extending pockets therein, which are filled with packing material simultaneously as the pockets are formed.

When built into the padding as hereinbefore described, the bats 10 will underlie the ribbed construction of the outer finish covering of the upholstery and give the same the desired ribbed or corrugated appearance. The bats 10 are continuous, tubular elements of batting or the like constructed of resilient fibrous material, such as cotton, hair, jute, wood wool, or various combinations of these materials, although a combination of very short staple cotton and wood wool is preferred on account of the cheapness of this material. The bats are preferably of homogeneous cross-section, and may be advantageously employed without any reinforcement, thus avoiding the necessity of continuous strips of paper or the like running therethrough, and without requiring external binding, such as a reinforcing envelope of paper or fabric.

The backing sheet 11 is preferably of a coarse fabric, such as burlap, muslin or other suitable material, which is adapted to engage the springs of the upholstery and transmit stresses thereto from the padding, and to prevent the springs from penetrating the padding.

The cover which is spread over the bats 10 may be a sheet of padding 12 which may be constructed of any of the materials given for the bats 10 and may be reenforced as desired, 5 the sheet 12 extending over a plurality of adjacent bats 10 and being stitched to the backing sheet 11 therebetween, as by lines of stitching 13. This sheet of batting is of considerable thickness, and gives body to the 10 finished pad as a whole, and as it overlies the bats 10, it gives a smoothly rounded contour to the ribs of the finished padding.

Above the batting 12 is preferably provided a cover sheet of rough unfinished or lining material 14 which is stitched to the backing 15 11 along with the batting 12 and serves to retain the fibers of the batting 12. The sheet 14 is preferably of loosely woven, open or net construction, and may be scrim, muslin, 20 cheesecloth or the like, tobacco cloth being preferred for this purpose. This feature is of considerable importance, as the construction of the bats 10 and batting sheet 12 is necessarily loosely assembled fibers which may 25 be easily disrupted in handling, and such disruption would cause an uneven contour and resiliency in the finished product.

For very cheap construction, the batting 30 12 may be omitted, in which case the cover sheet 14 will constitute a cover for the bats 10, and protect the fibers thereof from disruption. Conversely, for more elaborate up- 35 holstery, a filler sheet 15 of batting, similar to sheet 12, may be interposed between the backing 11 and the bats 10, and thus give the padding considerably more body.

The padding may be manufactured by the 40 machine illustrated in Figs. 2, 3 and 4. A table 16 is supported on a frame 17 and carries vertical supports 18 at the sides thereof which carry transversely extending bars 19. Depending from the bars 19 are a plurality 45 of slats 20 extending longitudinally of the table and depending toward the same, but clear thereof a sufficient distance to permit free passage of the backing 11.

Associated with the table 16 is a gang 50 stitcher of known construction and of which only the presser feet 21 and needles 22 are shown. These elements are located between the table 16 and a pair of coacting rollers 23 and 24 suitably driven so as to engage the finished padding therebetween and draw the same from the machine. In the form shown, 55 the traction of these rollers 23 and 24 furnishes all of the power for feeding the various elements.

The backing sheet 11 is supplied from a 60 roll 25 carried by a shaft 26 suitably supported by the frame 17. The bats 10 are supplied from rolls, not shown, or from containers in which they have been folded in a back-and-forth manner so as to permit ready, continuous withdrawal therefrom. The bats 10 65 thus pass on to the backing sheet 11, which

forms a carrier therefor. This arrangement is of advantage with bats which have little tensile strength, and hence might become deformed or pull in two, without the support 70 of the sheet 11.

The batting 12 is supplied from a roll 27 carried by a shaft 28 suitably carried by the frame 17 above the table 16. In the form shown, the cover sheet 14 has been placed on the batting 12 in the operation of manufacturing the batting, and wound therewith on the roll 27 so that the product of the batting making machine may be merely mounted on the shaft 28 and fed therefrom into the machine according to the present invention. 75

A presser roller 29 is located adjacent the presser feet 21 and may be merely a tubular element of the desired weight for holding down the various layers, but in the preferred embodiment shown, the roll 29 has collars 30 80 thereon, one opposite each presser foot 21 so as to depress portions of the cover 12 or 14 between the bats 10 to facilitate the stitching of the sheets together by the needles 22 between the bats 10. 90

The slats 20 guide and space the bats 10 uniformly and accurately a sufficient distance to permit the bats to spread slightly from the elliptical form shown in Fig. 5, and taper down to a fine edge at each side, as shown in Figs. 6 and 7, and still leave clearance 95 therebetween so as to avoid overlapping or bunching under the needles 22.

The padding manufactured as described above, when cut into desired lengths to fit 100 respective automobile seat backs, may be covered with upholstery finish material by stitching the same thereto adjacent the lines of stitching 13. The finish material may be folded back and stitched again to conceal 105 the first stitch, and so on across the seat back, thus providing hidden stitching.

The ribs of this padding are of the proper 110 shape for the purpose intended, uniform in contour and resiliency. The batting 12 or 15 provides sufficient mat to give body to the padding as a whole. The sheet of batting 12, as it is pressed down over the bats 10 and stitched to the backing 11, serves to 115 slightly compress the bat evenly all around and at the same time a slight tension is set up in the batting 12 over the bat. Thus there is a thinning of the batting 12 at each side of the bat 10, which results in giving more of a crown to the rib of the finished padding. Furthermore, the batting 12 also serves to 120 fill in and smooth out any unevenness or irregularity in the bat 10. Thus the batting 12 not only furnishes added material to build up the crown and fill in voids or depressions in the bat 10, but also tends to confine and shape the bat, so that the finished ribs are smooth and uniform in contour. 125

The continuous method of manufacture results in speed of production, and reduces 130

manufacturing costs, as well as contributes to the uniformity of the product, as to spacing, resiliency, and contour. Furthermore, these advantages are accomplished by the use of 5 staple materials, simple operations and machinery, and an economical amount of power and labor.

While several embodiments of the invention have been illustrated and described in 10 such detail as to enable any one skilled in the art to practice the invention, nevertheless it will be understood that the invention is not limited to the details disclosed other than as necessitated by the development of the 15 prior art, but, instead, it is to be understood that the invention embraces such embodiments of the broad idea as fall within the scope of the appended claims, it being obvious that various modifications, substitutions 20 and other changes may be made without departing from the spirit of the invention.

Having thus described our invention, we claim:

- 25 1. Upholstery padding comprising a backing sheet, a sheet of batting, bats between said sheets, and lines of stitching connecting said sheets between said bats.
2. Upholstery padding comprising a backing sheet, a cover sheet, a layer of batting and a layer of bats between said sheets, and lines of stitching connecting said sheets and batting between said bats.
3. Upholstery padding comprising a backing sheet, a layer of bats on said backing sheet, a layer of batting over said bats, and a sheet of retaining material over said batting, said sheets and batting being stitched together between said bats.
- 40 4. Upholstery padding comprising a backing sheet, a sheet of netting, a layer of bats and a layer of batting between said sheets, said sheets and batting being secured together between said bats.
- 45 5. Upholstery padding comprising a sheet of burlap, a layer of closely spaced parallel preformed tubular bats of resilient fibrous padding material extending longitudinally of said burlap, a transversely and longitudinally continuous layer of batting over said bats, a sheet of tobacco cloth over said batting, said burlap, batting and tobacco cloth being stitched together between said bats.

In testimony whereof, we hereunto affix 55 our signatures.

LE-ROY V. GORDON.
LEO L. WILLIAMS.
